CLAIM

The ornamental design for a sports glove with removable palm containing a peripheral panel, as shown and described.

DESCRIPTION

FIG. 1 is a front perspective view of a sports glove with removable palm containing a peripheral panel according to the present invention;

FIG. 2 is a front elevation view thereof;

FIG. 3 is a top plan view thereof;

FIG. 4 is a rear elevation view thereof;

FIG. 5 is a bottom plan view thereof;

FIG. 6 is a left side view thereof; and,

FIG. 7 is a right side view.

The broken lines shown in the figures that are immediately adjacent to the shaded areas and define regions that are consistently unshaded, represent the bounds of the claim, while all other broken lines, including those within the broken line boundaries, are directed to portions of the glove; the broken lines form no part of the claimed design.
